UNITED STATES PATENT OFFICE.

ALBERT DELAS, OF PARIS, FRANCE.

STEAM EJECTOR WITH COOLED DIFFUSER.

Application filed October 31, 1918, Serial No. 260,601½, and in France September 6, 1918.

In the construction of ejectors of a high ratio of compression it has heretofore been the practice to give the diffuser a convergent-divergent form. This form however, is only suitable when the normal ratio of compression has been attained, as the starting operation is very difficult. It is difficult to start because the density of the fluid in the nozzle chamber is much higher than that which must prevail under normal operation. Consequently, the jet of steam which is employed as the motive fluid, not only spreads out but loses a part of its speed by virtue of this denser atmosphere, and for a predetermined surface the weight of the fluid that it carries along is considerably increased, due to the high density of this fluid. Therefore, if the distance from the nozzle to the neck of the diffuser has been calculated and proportioned for the maximum efficiency under normal operation the jet of steam will strike the inside wall of the diffuser and the ejector will not start. For the same reason the vacuum will fall down (technically known as upsetting) if, during normal operation, some abnormal quantity of fluid rushes in. In order to avoid these difficulties the various builders, up to the present time, have been obliged to construct the neck of the diffuser for the maximum weight of the fluid to be extracted, and not for normal operation. Also the diffuser in general has been constructed more open, than would otherwise be required, in order that the steam, which spreads out at starting, should not touch its inner wall.

The apparatuses just described have an important bearing on the normal operation because, if the neck of the diffuser is too large for normal operation, the fluid column forced into the diffuser will have a contracted section which is smaller than the neck of the diffuser and will therefore not fit the sides of the diffuser; and from the moment that the fluid column leaves said sides eddies will be formed which interfere with the output and with the stability of the ejector. To overcome this builders have been obliged to admit extraneous air or other fluid into the diffuser in order that the latter may always be filled, thereby preventing the column from expanding and thus giving rise to eddies. The loss of efficiency due to the work necessary to compress this air or other fluid admitted is considerable but necessary to stabilize the

apparatus. But it is obvious that the maximum of efficiency with such an apparatus is obtained only at the moment of starting and for the poor vacuum. After having used it exclusively certain builders have given up this process of stabilization as too costly and sacrifice both the efficiency and the stability by employing some intermediary method.

Furthermore, in order to allow the starting in certain types of apparatus, it has been necessary to use several nozzles, instead of one, and to reduce the total surface according to the laws governing the quantities of movement under normal operation. This again sacrifices the efficiency, and the use of several nozzles necessitates an extreme reduction in the dimensions of the neck of the nozzles—few tenths of a millimeter. Those nozzles introduce another undesirable characteristic; that is, they are frequently obstructed because of some unfiltered deposits carried along by the motive fluid.

It may therefore be briefly stated that, among others, attempts to stabilize ejectors, the ratio of compression of which are necessarily subject to fluctuations, have been made either by providing air inlets at the throat of the diffuser or in the space in which the vacuum is maintained, or by varying the cross-sectional area of the throat of the diffuser, either automatically or otherwise in accordance with the ratio of compression, and by varying the amount of motive fluid admitted.

My present invention is an improvement upon my Patent No. 1,874,990 dated April 19, 1921, the object being to more effectively insure automatic stability, irrespective of the ratio of compression, without admitting air, without varying the amount of working steam, and without varying the cross-sectional area of the throat.

An ejector constructed along conventional lines was equipped with a cooling means and tested out. As compared with a similar device, where the cooling was carried on at the divergent portion only, very little difference in effect could be noticed. This leads to the conclusion that it is useless, from a practical standpoint, to provide the divergent portion of the conventional type of ejector with a cooling means since the results are not improved thereby. It is only desirable when the angle of divergence is decreased,

or when that angle is made zero or negative, that its cooling becomes important. One of the more important objects of the present invention therefore consists in providing a cooling action upon the divergent so as to enable it to be made of substantially cylindrical forms, this form having the advantages of being easy to construct and greater stability in the production of higher vacuums.

It is a matter of common knowledge that the steam issuing from the nozzles, during the production of high vacuums, has the shape of a cone the length of which increases in proportion to the reduction of the pressure. Consequently, the neck of the steam jet displaces itself downwardly with reference to the neck of the diffuser. If in this displacement the cross sectional area of this shifting neck can be maintained constant the equilibrium or stability will likewise be maintained, and to accomplish this the usual diverging portion is made cylindrical or substantially so. And with this explanation it will now be obvious to those skilled in this art that in the production of higher vacuums a greater stability is assured. In the ordinary form of diffuser the displacement of the neck of the steam jet effects an increase in its cross-sectional area with a result of "upsetting" of the device because the momentum per unit of surface is being reduced; or in any case there will result detrimental pulsations. Furthermore I have found, when the usual divergent portion is made of cylindrical form, that the ability of the device to extract a fluid is not impaired in the least.

I have therefore found that the angle of divergence of the diffuser may be reduced since the cold wall compensates for the lack of divergence by condensing a certain amount of fluid. For this reason it becomes possible to reduce the angle of divergence to zero, that is to say, it enables the substitution of a cylindrical pipe with cooled walls for the ordinary form of the diverging portion of a diffuser. This will in no way impair the efficiency, and it enables the throat to shift over the entire cylindrical length, at the same time imparting great stability to the apparatus and greatly facilitating its construction. The angle of divergence may even be made negative, that is, the ordinary divergent portion of the diffuser may be made convergent. This type of ejector may be readily adapted to all cases, more particularly in the case where two or more steam ejectors are separated by one or more intermediate condensers, a very advantageously arranged apparatus is secured. The circulating water, which has been employed to cool the wall of the upper diffuser may, by means of holes provided in the wall, be made to enter said diffuser for the purpose of con-

densing the steam coming from the upper ejector and be returned to the main condenser or removed by suitable means.

Although no claim is made to multi-stage ejector systems in the present application this subject-matter is claimed in my co-pending applications Serial Nos. 324,391 and 396,018.

The annexed drawing shows, by way of example and in axial section, one of the elements of my improved ejector and its intermediate condenser.

The reference letter *a* designates a nozzle, only one being illustrated, but it is obvious that a plurality of the same may be employed. However, the automatic starting effected by the system which forms the subject matter of my patent above referred to enables the use of a single nozzle while at the same time preserving a large effective area. The converging portion of the diffuser is illustrated at *b*, while the diffuser portion is illustrated at *c*, the latter, in the form of the device shown, comprising a cylindrical pipe. The throat is located at *c*. The entire diffuser is surrounded by a casing *d* and it is between this casing and the wall of the diffuser that the cooling medium is adapted to circulate.

The walls in contact with the working or motive fluid, and more particularly those of the nozzle and diffuser, are preferably nickel-plated, in whole or in part, in order, primarily, to minimize the friction of the fluid. A very simple method of constructing the walls consists in producing them by electrolytic means, for example, by a deposit of copper upon a mold in a bath, such deposit, by the same means, being subsequently covered with nickel at the points where such coating is desired. This method of manufacture admits of ready interchange of heat through the walls.

When the ejector is combined with a condenser it is furthermore provided with holes *h* in the section *f* of the divergent portion corresponding practically to a point where the required pressure prevails for delivery into the intermediate condenser *g*. Said holes *h*, provided in pipe *c*, owing to the relative vacuum prevailing in the apparatus, enables the circulating water, which has been used to cool the diffuser and which is under higher pressure to enter the interior. Beginning at this cross section *f* the pipe (the inlet tube, may be made convergent, divergent or cylindrical.

It is also possible to begin the injection of water at a point upward from said section *f*. Such injection may even begin at the throat of the divergent portion in order to complete by mixture the condensation on the surfaces formed by the cooled wall of the diffuser. In certain special cases such condensation by injection is capable of being employed

alone. In any event, the water condenses the steam so that at the discharge of the pipe *e* into the intermediate condenser there is practically only the ejected fluid and water, to the exclusion of all steam.

The hot water is drawn off through the pipe *j* and the air through the pipe *k* which is concentric with the steam pipe of the succeeding ejector.

10 The diffuser is located almost wholly in the intermediate condenser *g* in order to reduce the total bulk of the apparatus. On the other hand, the air drawn in through the inlet pipe ascends through its by-pass in 15 the direction of the arrow *l*, which by-pass is formed by the tube prolonging the diffuser and the outer wall *m* which receives the cooling or condensing water, so that the air may be cooled by contact with it and so that the 20 vapor which may not have completely condensed, may finish its condensation.

The diffuser is fixed at its upper part, but it passes freely through ring *n* at its lower end so as to enable it to expand freely and 25 so that a stream of water may also be provided at this point over the entire periphery in order to accelerate the condensation.

From the foregoing description it will be clear that I have not only designed an apparatus but also provided a method by which 30 the stability of an ejector is effected for all conditions of normal and abnormal operation, and also for the conditions which prevail in the starting of the apparatus; and at 35 the same time enabling a maximum efficiency of the apparatus when operating under normal conditions of working. It will also be apparent that I have made provisions in the same apparatus and method for completing 40 or practically completing the condensation of the uncondensed vapors flowing into the intermediate condenser.

What I claim is:—

1. In an ejector, the combination of a 45 nozzle for the motive fluid, an inlet for the fluid to be exhausted, a diffuser provided with a converging portion, a neck portion and an outlet portion, the inlet of said converging portion having a cross sectional area greater than that of any other portion of 50 said diffuser and means comprising a cooling jacket surrounding all portions of said diffuser for condensing the motive fluid which is in excess of working conditions required 55 in any portion of the diffuser.

2. In an ejector, the combination of a 60 nozzle for the motive fluid, an inlet for the fluid to be exhausted, a diffuser provided with a converging portion, a neck portion and an outlet portion, the inlet of said converging portion having a cross sectional area greater than that of any other portion of 65 said diffuser and means comprising a cooling jacket surrounding all portions of said

diffuser for condensing any eddies in the 65 diffuser in the operation of the same.

3. An ejector of a high ratio of compression comprising a diffuser having a converging inlet portion, a neck portion, and an outlet portion whose maximum cross-section 70 is substantially the same as that of said neck portion, and a cooling means for all portions of the diffuser.

4. An ejector of a high ratio of compression comprising a diffuser having an outlet 75 portion of substantially cylindrical form to maintain the neck portion of the steam jet constant as it shifts in the production of high vacuums, in combination with cooling means for said portion.

5. An ejector of a high ratio of compression comprising a diffuser having an inlet portion of usual form and an outlet portion of substantially cylindrical form for the 80 purpose described, in combination with cooling means for said portions.

6. An ejector of high ratio of compression comprising a diffuser having an inlet portion and neck portion of usual forms and 85 an outlet portion of substantially cylindrical form for the purpose described, in combination with cooling means for said inlet, neck and outlet portions.

7. A construction of an ejector as defined in claim 5, in which provisions are made for 90 cooling fluid to enter the outlet portion of the diffuser to further condense the motive fluid moving through the ejector.

8. The process of ejecting a fluid which 95 consists in passing a motive fluid through a diffuser in a quantity sufficient to provide for the normal ratio of compression, maintaining the cross-sectional area of the neck portion of the steam jet substantially constant 100 as it shifts along the diffuser, and condensing the excess motive fluid passing therethrough.

9. The process of ejecting a fluid which 105 consists in passing a motive fluid through a diffuser in a quantity sufficient to provide for the normal ratio of compression, maintaining the cross-sectional area of the neck portion of the steam jet substantially constant 110 as it shifts along the diffuser, and maintaining the outlet portion of the diffuser at a relatively low temperature to condense any eddies or excess fluid passing therethrough.

10. The process of ejecting a fluid which 115 consists in passing a motive fluid through a diffuser in a quantity sufficient to provide for the normal ratio of compression, maintaining the cross-sectional area of the neck portion of the steam jet substantially constant 120 as it shifts along the diffuser, and maintaining the inlet and outlet portions of the diffuser at a relatively low temperature to condense any eddies or excess fluid passing therethrough.

11. The process of ejecting a fluid which consists in passing a motive fluid through a diffuser in a quantity sufficient to provide for the normal ratio of compression, maintaining the cross-sectional area of the neck portion of the steam jet substantially constant as it shifts along the diffuser, and maintaining the inlet, neck and outlet portions of the diffuser at a relatively low temperature to condense any eddies or excess fluid passing therethrough.
12. A process as defined in claim 9, comprising the additional step of admitting at least a portion of the condensing fluid employed into the outlet portion of the diffuser to further condense the motive fluid moving through the ejector.
13. A construction of an ejector as defined in claim 6, in which provisions are made for cooling fluid to enter the outlet portion of the diffuser to further condense the motive fluid moving through the ejector.
14. A construction of an ejector as defined in claim 7, in which provisions are made for cooling fluid to enter the outlet portion of the diffuser to further condense the motive fluid moving through the ejector.
15. A process as defined in claim 10, comprising the additional step of admitting at least a portion of the condensing fluid employed into the outlet portion of the diffuser to further condense the motive fluid moving through the ejector.
16. A process as defined in claim 11, comprising the additional step of admitting at least a portion of the condensing fluid employed into the outlet portion of the diffuser to further condense the motive fluid moving through the ejector.
17. A process as defined in claim 12, comprising the additional step of admitting at least a portion of the condensing fluid employed into the outlet portion of the diffuser to further condense the motive fluid moving through the ejector.
18. An ejector comprising in combination, a tubular diffuser, a cooling jacket for said diffuser, and a casing surrounding said diffuser and jacket.
19. An ejector comprising in combination, a diffuser, a sleeve surrounding said diffuser, inlet means for supplying cooling fluid to the interior of said sleeve and exit means for said fluid, and a casing surrounding said sleeve.
20. An ejector comprising in combination, a casing, a tubular diffuser extending into said casing, means connecting said diffuser and casing but permitting relative movement of the same upon variation in temperature, and means for passing cooling fluid through said casing in contact with the exterior of said diffuser.
21. An ejector comprising in combination, a casing, a diffuser extending into said cas-
- ing, means connecting said diffuser and casing but permitting relative movement of the same upon variation in temperature, a sleeve surrounding said diffuser, and means for passing cooling fluid through said casing between said diffuser and sleeve.
22. An ejector comprising in combination, a casing, a tubular diffuser fixed thereto at one end but capable of movement with respect thereto at its other end, said casing surrounding said diffuser, and means for supplying elastic motive fluid to said diffuser.
23. An ejector comprising in combination, a tubular diffuser, a combining chamber in communication with one end of said diffuser, a sleeve surrounding said diffuser closely adjacent thereto, means for supplying a current of cooling fluid to the interior of said sleeve, and a casing surrounding said sleeve.
24. An air and non-condensable fluid ejector for a steampower-plant condenser wherein a low absolute or highly vacuous pressure normally obtains comprising a chamber adapted for communication with apparatus of the character designated, a diffuser communicating with the chamber, an expanding nozzle of the divergent type for transforming steam at high pressure into steam having low absolute or highly vacuous pressure and moving at high velocity and for discharging the high-velocity steam in a jet across at least a portion of the space of said chamber and into said diffuser, the high velocity jet entraining air and non-condensable fluids from said chamber and the mixture of steam, air and non-condensable fluids undergoing velocity-pressure conversion in the diffuser, and means co-operating with the diffuser, including the converging portion thereof, for condensing such part of the steam of the mixture that the volume of a given mass of mixture does not increase in its passage through the major portion of said diffuser in order to improve the performance of the ejector.
25. An air and non-condensable fluid ejector for a steampower-plant condenser wherein a low absolute or highly vacuous pressure normally obtains comprising a chamber adapted for communication with apparatus of the character designated, a diffuser communicating with the chamber, an expanding nozzle of the divergent type for transforming steam at high pressure into steam having low absolute or highly vacuous pressure and moving at high velocity for discharging the high-velocity steam in a jet across at least a portion of the space of said chamber and into said diffuser, the high velocity jet entraining air and non-condensable fluids from said chamber and the mixture of steam, air and non-condensable fluids undergoing velocity-pressure conversion in the diffuser,

and means co-operating with the diffuser, including converging, diverging and throat portions thereof, in order to condense such a portion of the steam of the mixture that the volume of a given mass of mixture does not increase in its passage through the major portion of said diffuser to improve the performance of the ejector.

26. An air and non-condensable fluid ejector for a steam-power plant condenser wherein in a low absolute or highly vacuous pressure normally obtains comprising a chamber adapted for communication with apparatus of the character designated, a diffuser communicating with the chamber, an expanding nozzle of the divergent type for transforming steam at high pressure into steam having low absolute or highly vacuous pressure and moving at high velocity and for discharging the high-velocity steam in a jet across at least a portion of the space of said chamber and into said diffuser, the high velocity jet entraining air and non-condensable fluids from said chamber and the mixture of steam, air and non-condensable fluids undergoing velocity-pressure conversion in the diffuser, and means co-operating with the diffuser for effecting condensation of such part of the steam of the mixture throughout the length of the diffuser that the volume of a given mass of mixture does not increase in its passage through the major portion of said diffuser in order to improve the performance of the ejector.

27. The process of ejecting a fluid which comprises passing an elastic motive fluid through an elastic fluid to be ejected to entrain said fluid passing the mixture through a diffuser and progressively cooling said mixture so that the volume of a given mass thereof at any point in said diffuser does not exceed the volume of said mass at a preceding point in its path through said diffuser.

28. The process of ejecting a fluid which comprises expanding an elastic motive fluid in contact with a second elastic fluid to be ejected, to entrain said fluid, and passing the mixture through a diffuser, and progressively cooling said mixture during its progress along said diffuser so that the volume of a given mass of said mixture is a maximum at the inlet of said diffuser.

29. The process of ejecting a fluid which comprises expanding steam in contact with the fluid to be ejected, to entrain said fluid, and passing the mixture through a diffuser, while regulating the temperature of said mixture during its progress through the diffuser, at such value that the volume of a given mass of mixture therein does not increase.

30. The process of ejecting a fluid which

comprises expanding steam in contact with the fluid to be ejected to entrain said fluid, passing the mixture through a diffuser, and progressively condensing such quantities of steam that the volume of a given mass of mixture never exceeds the volume of said mass at the inlet to said diffuser.

31. In an ejector, in combination, a casing, an inlet in said casing for motive fluid, a second inlet for fluid to be ejected, and a diffuser the cross sectional area of which is a maximum at the inlet thereof.

32. In an ejector, in combination, a casing, an inlet in said casing for motive fluid, a second inlet in said casing for fluid to be ejected, and a diffuser, the cross sectional area of said diffuser being no greater at any point therein than the cross-sectional area of any section between said point and the inlet thereof.

33. In an ejector, in combination, a casing, an inlet in said casing for motive fluid, a second inlet for fluid to be ejected, and a diffuser, said diffuser being mounted in said casing at one point only in the length thereof.

34. In an ejector, in combination, a casing, an inlet in said casing for motive fluid, a second inlet for fluid to be ejected, and a diffuser, said diffuser being mounted in said casing at the inlet thereof only and out of contact therewith at all other points.

35. In an ejector, in combination, a casing, an inlet in said casing for motive fluid, a second inlet for fluid to be ejected, a diffuser mounted in said casing by the inlet end only and out of contact with said casing at other points, and a chamber for cooling fluid surrounding said diffuser.

36. In an ejector, in combination, a casing, an inlet in said casing for motive fluid, a second inlet for fluid to be ejected, a diffuser mounted in said casing by the inlet end only and out of contact with said casing at other points, and a chamber for cooling liquid surrounding said diffuser, the bottom wall of said chamber being formed to provide for a flow of cooling liquid from said chamber about the end of said diffuser.

37. In an ejector, in combination, a casing, an inlet in said casing for motive fluid, a second inlet for fluid to be ejected, a diffuser mounted in said casing by the inlet end only and out of contact with said casing at other points, and a chamber for cooling liquid surrounding said diffuser, the bottom wall of said chamber being provided with an opening, and the outlet of said diffuser projecting therethrough.

In witness whereof I have hereunto signed my name.

ALBERT DELAS.
